RADIATOR CAP

Edward Lisota, Patterson, Calif.

Application April 14, 1949, Serial No. 87,513

1 Claim. (Cl. 220—86)

1

This invention is directed to, and it is an object to provide, an improved radiator cap for motor vehicles.

Another object of the invention is to provide a radiator cap which permits the radiator to be filled with water without removing the cap.

An additional object of the invention is to provide a radiator cap, as in the preceding paragraph, which is arranged to prevent the operator—upon filling the radiator—from being burned by contact with the hot cap or by steam blowing back from the radiator when the water in the latter is boiling and steaming.

A further object of the invention is to provide a radiator cap, characterized as above, which is designed for ease and economy of manufacture.

A further object of the invention is to provide a practical and reliable radiator cap, and one which will be exceedingly effective for the purpose for which it is designed.

These objects are accomplished by means of such structure and relative arrangement of parts as will fully appear by a perusal of the following specification and claim.

In the drawings:

Fig. 1 is an elevation of the cap detached.

Fig. 2 is an enlarged sectional elevation of the cap as in use and with the valve in its normal closed position.

Fig. 3 is a similar view but shows the cap with the valve opened by a water feed nozzle for filling the radiator.

Referring now more particularly to the characters of reference on the drawings, the radiator cap is indicated generally at 1, such cap including, as usual, a depending peripheral coupling collar 2 adapted for releasable connection with the annular locking flange 3 on the upper end of the filler neck 4 of the radiator. A conventional sealing gasket G is normally engaged between the cap 1 and annular locking flange 3.

A vertical, tubular stem 5 extends in slidable relation centrally through the cap 1, and through the central bore 6 of a rigid annular valve seat 7 affixed to the cap 1 mainly on the underside of the same and in downwardly facing relation.

At its lower or inner end the tubular stem 5 is formed with an enlarged, horizontal disc valve 8 having a gasket 9 on top thereof; such disc valve 8 normally abutting the annular valve seat 7 in closed relation, as in Fig. 2.

The disc valve 8 is yieldably maintained in such normal closed position by a loaded helical compression spring 10 which surrounds the tubular stem 5 between the top of the valve seat

2

7 and an enlarged radial flange 11 formed on the upper end of said stem 5.

An enlarged cylindrical head 12, of resilient material such as relatively soft rubber, surrounds the upper portion of the stem 5, and the radial flange 11 is embedded in such head intermediate the ends thereof.

The head 12 is funnel-like and includes a downwardly tapering hole 13 which leads from the upper end of said head to communication with the bore of the stem 5.

Below the radial flange 11 the head 12 is annularly recessed, as at 14, for the reception of the helical compression spring 10. Radially outwardly of the spring 10 the head 12 depends in the form of an annular skirt portion 15; the lower end of such skirt portion normally being spaced a distance above the top of the cap 1.

At its lower end, and immediately above the gasket 9, the stem 5 is formed with a plurality of laterally opening ports 16; such ports being closed by the annular valve seat 7 when the parts of the device are in their normal positions, as in Fig. 2.

25 When it is desired to fill the radiator with water, a water feed nozzle, indicated diagrammatically at 17, is engaged with a tight frictional fit in the tapered hole 13 of the head 12 and the nozzle 17 is then pressed downwardly causing the head 12 and the stem 5 to move downwardly. With such movement the horizontal disc valve 8 moves down from the valve seat 7 to an open position, as in Fig. 3, wherein the ports 16 open into the filler neck 4 of the radiator whereby water may then flow from the nozzle 17 through stem 5 and out of ports 16 into said filler neck 4.

It is thus possible to fill the radiator with water without the necessity of touching or removing the cap 1. This is extremely advantageous in an instance where the water in the radiator is initially low, boiling, and steaming; the device making it possible to fill the radiator without subjecting the operator to possible burning by the steam. With the described radiator cap it is impossible for steam to escape during the filling operation. This is due to the fact that the nozzle 17 makes a tight fit in the tapered hole 13 of the head 12, and additionally the annular depending skirt portion 15 of said head abuts the top of the cap 1 during the filling operation. Such abutment of the skirt portion 15 with the top of the cap 1, as in Fig. 3, assures that no steam can escape along the stem 5 and thence laterally outwardly above the cap.

55 The described radiator cap is a very practical

and reliable device for the intended purpose; the design of such cap being such that it can be manufactured simply and economically.

From the foregoing description it will be readily seen that there has been produced such a device as substantially fulfills the objects of the invention as set forth herein.

While this specification sets forth in detail, the present and preferred construction of the device, still in practice such deviations from such detail may be resorted to as do not form a departure from the spirit of the invention, as defined by the appended claim.

Having thus described the invention, the following is claimed as new and useful and upon 15 which Letters Patent are desired:

In a radiator cap, an upstanding stem slidably extending through the cap, a horizontal disc valve on the lower end of the stem, a port in the stem directly above the disc valve, an annular valve seat on the cap, a radial flange on the stem above the cap, a helical compression spring surrounding the stem below said radial flange and normally but yieldably urging the stem upward to close the valve against the seat, and a funnel- 25

like head of resilient material on the stem and in communication therewith; the radial flange being embedded in said head and the latter being adapted to receive a water feed nozzle therein in close fitting relation; there being an annular depending skirt portion on the head about the stem and spring, said skirt portion having a wide relatively flat under surface, such surface being normally spaced above the cap but moving into face to face relation therewith upon downward motion of the stem caused by pressure of the nozzle on said head.

EDWARD LISOTA.
